UNITED STATES PATENT OFFICE.

CHARLES H. FROST, OF PASADENA, CALIFORNIA, ASSIGNOR TO LOS ANGELES
PRESSED BRICK CO., A CORPORATION OF CALIFORNIA.

BRICKMAKING-MACHINE.

1,004,406.

Specification of Letters Patent. Patented Sept. 26, 1911.

Application filed September 10, 1907. Serial No. 392,226.

To all whom it may concern:

Be it known that I, CHARLES H. FROST, a citizen of the United States, residing at Pasadena, in the county of Los Angeles and State of California, have invented new and useful Improvements in Brickmaking-Machines, of which the following is a specification.

This invention relates to improvements in brick making machinery designed to produce a brick, particularly paving brick, which is laid edgewise and the flat face of which must be separated from the flat face of the adjacent brick to permit the grouting or cement to be introduced between the brick, and the object of the present invention is to provide an improved construction whereby the brick is formed with a plurality of projections on its face which will hold the brick a slight distance from the adjacent brick and yet will allow the mortar or cement to flow down to the bottom of the crack between the two bricks, so that the space between the bricks is completely filled by the mortar and the bricks thus firmly cemented in place.

Referring to the drawings:—Figure 1 is a side elevation, partly in section, of a portion of a brick making machine constructed with my improvements. Fig. 2 is a plan view of the improved portion of the machine. Fig. 3 is a perspective view of a brick constructed by a machine embodying my improvements.

The brick 1 to be constructed is shown in Fig. 3 and is provided with two rows of projections 2, the projections 2 extending sufficiently from the face of the brick to prevent the flat face of the brick from contacting with the adjacent brick and to thus form a space for the mortar, and the spaces 3 between the respective projections to permit the mortar to flow down so as to completely fill the space between two adjacent bricks. In constructing this brick, the plastic is run out from the press 4 in a continuous bar 5, the press 4 forming two ridges 6 on top of the bar 5, as clearly shown in Fig. 2. As the bar 5 travels in the direction of the arrow, being pushed from the press 4, it rides on a traveling belt 7 supported at suitable intervals by rollers 8 as shown in Fig. 1, and the ridges 6 are indented by a rotating wheel 9, the surface of which is provided with longitudinal parallel ribs 10,

the ribs 10 pressing down into the ridges 6 of the plastic as the bar 5 runs under the wheel 9, so that as the bar issues beyond the wheel 10 the ridges 6 are notched as shown, thus forming the projections 2 indicated in Fig. 3.

The wheel 9 is mounted in journals 11 on a frame 12 hinged at 13 to brackets 14. The swinging ends of frame 12 are guided by vertical posts 15, and coil springs 16 are arranged above the bars of frame 12 to secure the necessary pressure of wheel 9 against the bar 5. Nuts 17 are arranged on posts 15 to prevent the frame 12 swinging too far down so that the ribs 10 indent deeper than the height of the ridges 6. By adjusting nuts 18 on posts 15 the tension of springs 16 may be regulated to the desired degree. After leaving the wheel 9 the bar 5 is cut at regular intervals by wires 19 carried by a rotating spider 20 and the bricks are carried away from the cutter on a traveling belt 21, the speed of which is greater than belt 7, so that as the bricks leave the cutter they are spaced apart on belt 21 permitting them to be readily removed therefrom.

It is not necessary to operate the wheel 9 by mechanical means as the indentation of its ribs 10 in the ridges 6 is sufficient to give the wheel rotation.

As shown in the drawings the ribs 10 are formed separately from the wheel 9, but it is obvious that the wheel 9 and ribs 10 could easily be cast as one integral piece if desired.

It is important to note that the notches formed in the ridges 6 are not produced by cutting out portions of the ridges, but are produced by indentation of the ribs 10, and there is thus no material removed from the ridges 6 to lie on the bar as would be the case if the notches were cut out, as the removal of such cut out plastic is a difficult matter. Moreover, it is difficult to cut out the notches without tearing or roughening the plastic. By producing the notches by indentation, however, the slight amount of plastic which originally filled each notch is compressed into the bar instead of being removed, and thus the walls of the notches are very smooth and there is no loose material which has to be removed from the bar 5.

What I claim is:—

1. In a brick machine, means for forming a bar of plastic material with parallel ridges upon one side at a distance apart, a ribbed

wheel journaled with its axis above and at right angles to the movement of said bar and its ribs adapted to engage with and indent said ridges even with the top of the 5 bar, and means for severing the bar into lengths transversely of said ridges.

2. In a brick machine, a support, brackets and screw threaded posts thereon, a frame hinged to the brackets at one end and 10 adapted to fit over said posts at the other, a pair of nuts on each post, one upon each side of said frame, a spring between the top of the frame and the upper nut, a ribbed wheel journaled in said frame, means for 15 carrying a bar of plastic material with parallel ribs on its upper face under said

wheel, whereby the ribs are indented, and means for severing said bar into lengths.

3. In a brick machine, means for forming a rectangular block of plastic material having a plurality of longitudinal ridges upon 20 one side, and means for forming each of said ridges into a plurality of projections subsequent to the formation of the ridges.

In testimony whereof, I have hereunto set 25 my hand at Los Angeles, California, this 3d day of September 1907.

CHARLES H. FROST.
